MAGIC TRICK APPARATUS

Mont Davis, Jr., and Ruth F. Davis, Martha, Tenn.

Application August 10, 1948, Serial No. 43,406

2 Claims. (Cl. 272—8)

1

This invention relates to magic trick apparatus which we prefer to term a "Pent-a-Penny," for performing magic coin tricks and other tricks.

The main object of our invention is to provide magic trick apparatus for producing optical illusions in order to mystify and amuse.

Another object is to provide such trick apparatus which makes it readily possible to deceive the eye in order to perform seemingly impossible feats to the entertainment and astonishment of spectators.

A further object is to have such apparatus include a pair of substantially equal blocks with holes therethrough and also a long nail or rod used therewith.

It is also an educational object of the invention to train the eye and the hand by means of the apparatus of the invention.

Other objects and advantages of this invention will appear in further detail as the specification proceeds.

In order to facilitate ready comprehension of this invention for a proper appreciation of the salient features thereof, the invention is illustrated on the accompanying drawing forming part hereof, and in which:

Figure 1 is a perspective view of a magic trick apparatus made according to the invention, the blocks of the apparatus being spaced apart to disclose detail;

Figure 2 is a vertical section taken on line 2—2 in Figure 1;

Figure 3 is a plan view of the normally inner mutual facing sides of the two trick blocks forming the major portion of the present magic trick apparatus so disposed to disclose details and mutual relations.

In the views the same reference numerals indicate the same parts.

In devices and apparatus used for sleight of hand, magic tricks and the like, it is always a question of using optical illusion in some manner or form to produce the desired appearances and effects. In some cases it is possible to train the eye and to detect and follow the operation that actually occurs, whereby to interpret what apparently occurs. With these thoughts in mind and also to provide apparatus for entertainment, amusement and to educate the eye and the hand, we have succeeded in producing a magic trick apparatus with considerable capacity for mystification and amusement now to be particularly described.

Hence, in the practice of our invention, and referring again to the drawing, a pair of rectan-

2

gular blocks 4 and 5 are made substantially equal in size and adapted in use to be superposed in coextensive relation as substantially shown in Figure 2, for example. Perpendicularly through

5 the upper block 4 are drilled three equidistantly spaced holes 6, 7 and 8 which are arranged in line along the central axis of the block, that is, equidistantly between the two side edges 9 and 10. The first hole 6 is disposed but a short distance 10 from the end 11 of block 4, whereas the other end of the series at hole 8 is disposed a relatively longer distance from the other end 12 of the same block, and in fact, the distance is sufficient so that a further hole could be spaced within end 15 12 substantially at the same distance therefrom as the hole 6 is from the end 11, and this latter hole would then be the same distance from the end hole 8 as hole 8 is from hole 7 or hole 6 is from hole 1.

20 In similar fashion, block 5 is provided with three holes 13, 14 and 15, spaced in substantially the same manner as holes 6, 7 and 8 on block 4, the first hole 13 being spaced a short distance from the end 17 of block 5, while the other end hole 15 is disposed a relatively greater distance from the end 16. While the holes 6, 7 and 8 are

25 uniform in diameter throughout their length so that they begin upon the upper surface 18 of block 4 at the same diameter as they terminate on the under side 19, the holes 13, 14 and 15 on the upper side 20 of block 5 are counterbored to a short depth to have a relatively large diameter, as shown at 21, 22, 23, which is sufficient to receive a coin 24 in each case in the mentioned

30 upper surface 20, so that the coin when deposited in the counterbored portions 21, 22, or 23, will be flush with the upper surface 20 of the block. These counterbored portions or recesses 21, 22 and 23 are only provided in block 5 and solely in the upper surface 20 already mentioned, while the bottom 25 is similar to either side 18 or 19 of block 4, wherein the holes are of the same uniform diameter throughout and not increased in diameter at the surface.

35 45 As best seen in Figure 2, the spacing of the holes 6, 7 and 8 in block 4 and the holes 13, 14 and 15 in block 5 is such in each case that if the upper block 4 is turned over on either side, as for example shown in Figure 3, the holes will present the same appearance whether the surface 18 or 19 is shown, but if the lower block 5 is turned end to end, as in the mentioned Figure 3, it will be noted that the spacing of the holes is

40 45 exactly the same in both blocks except for the circular recesses counterbored in the upper ends 55

of the holes 13, 14 and 15. When the lower block is turned about to occupy the position shown in Figure 1 or 2, with hole 13 remote from the hole 6 in block 4, it will be note that the holes 7 and 8 of the latter block register with holes 15 and 14, respectively, of block 5, and the hole 6 in block 4 terminates at the upper surface 20 of block 5, while hole 13 and its upper counterbored portion, or recess 21, face the lower blank surface 19 of upper block 4. In each case holes 6, 7, 8, 13, 14 and 15 are of substantially the same diameter and this is sufficient for allowing a nail or other elongated object 26 to be thrust through the holes when they are in registry, while the head 27 facilitates manipulating the nail and withdrawing it from the blocks.

The arrangement is such that if a performer displays the blocks substantially as shown in Figure 3 and lays the coin 24 into recess 22, that is, the intermediate recess between 21 and 23, and then very demonstratively closes the blocks together by laying the surface 19 of block 4 over the upper surface 20 of block 5, it is but a simple matter for him to turn block 4 end to end, or block 5 end over end, so that when the blocks approach each other they are substantially in the position with respect to each other as shown in Figure 1, and are brought together as illustrated in section in Figure 2. The act of switching one of the blocks endwise is, of course, intended to be done so swiftly that it will not be noticed, and then the performer will offer to thrust the nail through the coin which has been deposited in the intermediate recess 22 by inserting the nail 26 in the intermediate aperture 7 of upper block 4 and thrusting it all the way through to pass through block 5 as well. The illusion is created that the central aperture 22 containing coin 24 is directly beneath the hole 7, and thus it appears that the nail is being thrust through the coin as well as block 5 by the beholders imagining that block 5 remains as originally shown, that is, as it appears down at the bottom of Figure 3, with the holes 6, 7 and 8 aligned with holes 13, 14 and 15, which, however, is not the case, due to the switching of the lower block. If the upper block has been switched instead, the effect is, of course, the same on the spectators, namely, that the middle hole 7 is thought to be directly over recess 22 containing the coin 24.

When the blocks are again taken apart with the nail 26 removed, the previously-switched block is again returned to its original position, so that the two blocks again present the appearance relative to each other as shown in Figure 3, with the exception that the coin 24 perhaps remains in recess 22 to further mystify the beholders inasmuch as it is, of course, free from any aperture or any mark indicating that the nail has gone through. The entire procedure is, of course, a method of deceiving the eye by such swift motion of the hands that the switching of one of the blocks is not noted. The blocks are, of course, preferably made of wood or plastic or any other suitable material, and the holes 6, 7, 8, 13, 14 and

15, as well as the counterbored recesses 21, 22 and 23 very cleanly cut so that the finish and the appearance will be entirely satisfactory for demonstration purposes.

5 Manifestly, variations in size and numbers of holes and other modifications may be resorted to, and similar changes may be introduced within the scope of the appended claims.

Having now fully described our invention, we claim:

1. A magic trick apparatus including a pair of rectangular and substantially similar blocks having a row of holes extending transversely through both blocks from the upper surfaces to the lower surfaces thereof, the holes in each block being disposed in an equidistantly-spaced series midway between the side edges of the block and the first hole at one end of the series being spaced a shorter distance from the respectively adjacent end of the block and the last hole at the other end of the series spaced from the other end of the same block, the arrangement being such that in one superposed coextensive position of the blocks all the holes in one block register with all the holes in the other block, but in an opposite superposed coextensive position of the blocks wherein one block is reversed end to end one end hole in each block is disposed beyond the series in the other block while the remaining holes in both blocks register with each other, and one block upon the upper surface thereof having a shallow counterbored recess of sufficiently large diameter to receive a coin concentric with each of the holes therein.
2. A magic trick apparatus including a pair of rectangular and substantially similar blocks having a row of holes extending transversely through both blocks from the upper surfaces to the lower surfaces thereof, the holes in each block being disposed in an equidistantly-spaced series midway between the side edges of the block and the first hole at one end of the series being spaced a shorter distance from the respectively adjacent end of the block and the last hole at the other end of the series spaced from the other end of the same block, the arrangement being such that in one superposed coextensive position of the blocks all the holes in one block register with all the holes in the other block, but in an opposite superposed coextensive position of the blocks wherein one block is reversed end to end one end hole in each block is disposed beyond the series in the other block while the remaining holes in both blocks register with each other, and one block upon the upper surface thereof having a shallow counterbored recess of sufficiently large diameter to receive a coin concentric with each of the holes therein.
3. A magic trick apparatus including a pair of rectangular and substantially similar blocks having a row of holes extending transversely through both blocks from the upper surfaces to the lower surfaces thereof, the holes in each block being disposed in an equidistantly-spaced series midway between the side edges of the block and the first hole at one end of the series being spaced a shorter distance from the respectively adjacent end of the block and the last hole at the other end of the series spaced from the other end of the same block, the arrangement being such that in one superposed coextensive position of the blocks all the holes in one block register with all the holes in the other block, but in an opposite superposed coextensive position of the blocks wherein one block is reversed end to end one end hole in each block is disposed beyond the series in the other block while the remaining holes in both blocks register with each other, and one block upon the upper surface thereof having a shallow counterbored recess of sufficiently large diameter to receive a coin concentric with each of the holes therein.
4. A magic trick apparatus including a pair of rectangular and substantially similar blocks having a row of holes extending transversely through both blocks from the upper surfaces to the lower surfaces thereof, the holes in each block being disposed in an equidistantly-spaced series midway between the side edges of the block and the first hole at one end of the series being spaced a shorter distance from the respectively adjacent end of the block and the last hole at the other end of the series spaced from the other end of the same block, the arrangement being such that in one superposed coextensive position of the blocks all the holes in one block register with all the holes in the other block, but in an opposite superposed coextensive position of the blocks wherein one block is reversed end to end one end hole in each block is disposed beyond the series in the other block while the remaining holes in both blocks register with each other, and one block upon the upper surface thereof having a shallow counterbored recess of sufficiently large diameter to receive a coin concentric with each of the holes therein.
5. A magic trick apparatus including a pair of rectangular and substantially similar blocks having a row of holes extending transversely through both blocks from the upper surfaces to the lower surfaces thereof, the holes in each block being disposed in an equidistantly-spaced series midway between the side edges of the block and the first hole at one end of the series being spaced a shorter distance from the respectively adjacent end of the block and the last hole at the other end of the series spaced from the other end of the same block, the arrangement being such that in one superposed coextensive position of the blocks all the holes in one block register with all the holes in the other block, but in an opposite superposed coextensive position of the blocks wherein one block is reversed end to end one end hole in each block is disposed beyond the series in the other block while the remaining holes in both blocks register with each other, and one block upon the upper surface thereof having a shallow counterbored recess of sufficiently large diameter to receive a coin concentric with each of the holes therein.
6. A magic trick apparatus including a pair of rectangular and substantially similar blocks having a row of holes extending transversely through both blocks from the upper surfaces to the lower surfaces thereof, the holes in each block being disposed in an equidistantly-spaced series midway between the side edges of the block and the first hole at one end of the series being spaced a shorter distance from the respectively adjacent end of the block and the last hole at the other end of the series spaced from the other end of the same block, the arrangement being such that in one superposed coextensive position of the blocks all the holes in one block register with all the holes in the other block, but in an opposite superposed coextensive position of the blocks wherein one block is reversed end to end one end hole in each block is disposed beyond the series in the other block while the remaining holes in both blocks register with each other, and one block upon the upper surface thereof having a shallow counterbored recess of sufficiently large diameter to receive a coin concentric with each of the holes therein.
